MAGNETIC INDUCTION DEVICE

Charles G. Smith, Medford, Mass., assignor to
 Raytheon Manufacturing Company, Newton,
 Mass., a corporation of Delaware

Application July 24, 1946, Serial No. 685,939

8 Claims. (Cl. 250—27.5)

1

This invention relates to magnetic induction devices for accelerating charged particles, such as electrons, so as to cause the same to attain masses and velocities representing energies in the hundreds of millions of electron-volts, and constitutes a continuation-in-part of the invention disclosed in the copending application entitled "Magnetic induction devices," Serial No. 681,904, filed July 9, 1946.

Existing devices intended to attain the above-stated objective have suffered from the disadvantage of being limited, in imparting acceleration to the charged particles, to not more than a half-cycle of the driving electromotive force. In addition, such devices have required inordinately large amounts of iron to impart to the charged particles a given amount of energy.

It is, therefore, an object of the present invention to provide a magnetic induction device of the general character indicated which enables the repeated acceleration of the charged particles during many half-cycles of the driving electromotive force, thereby more easily attaining, with relatively weaker driving force, the extremely high energy desired.

It is another object of the present invention so to construct the above referred to magnetic induction device as to require, in order to arrive at a definite energy, the incorporation therein of considerably less iron than has heretofore been the case, thereby materially reducing cost, weight and size.

It is a further object of the present invention generally to improve the art of magnetic induction devices.

These and other objects of the present invention, which will become more apparent as the detailed description thereof progresses, are attained, briefly, in the following manner:

An evacuated envelope, made, preferably, of glass, and consisting, preferably, of a centrally-disposed, main body portion from which extends, in opposite directions, a pair of loop-like, auxiliary body portions communicating with said main body portion, is provided with means, for example, a conventional electron gun, for introducing electrons therein.

Spaced about at least a portion of one of the auxiliary body portions of said envelope is a plurality of means, preferably, electromagnetic, for establishing a plurality of magnetic fields transversely therethrough, said fields being constant or time varying, and acting upon the electrons emitted by said gun to subject the same to a first force the direction of which is per-

2

pendicular to the direction of said fields, whereby said electrons are caused to move in a first closed path including the main body portion and the last-mentioned auxiliary body portion of said envelope.

Also spaced about at least a portion of the last-mentioned body portion of said envelope is a plurality of means, preferably, electromagnetic, for establishing a plurality of time-varying magnetic fields linking said first closed path, said time-varying magnetic fields inducing a plurality of electromotive forces along the length of said first closed path, whereby the electrons moving therein are subjected to a second force which causes the same to become accelerated.

The main body portion of said envelope is provided with means, preferably, partially electromagnetic and partially electrostatic, for switching, after the first half-cycle of the driving electromotive force, the electrons accelerated as above, from said first closed path to a second closed path which includes the main body portion and the remaining auxiliary body portion of said envelope.

25 The last-mentioned auxiliary body portion of said envelope, like said first-mentioned auxiliary body portion, is provided with a plurality of means, preferably, electromagnetic, for subjecting the accelerated electrons received therein to a third force which causes the same to move in an orbit encompassing said second closed path. The last-mentioned auxiliary body portion of said envelope is also provided with a plurality of means, preferably, electromagnetic, for subjecting said accelerated electrons to a fourth force adapted additionally to accelerate the same.

30 The above referred to switching means is so designed that after the second half-cycle of the driving electromotive force, the electrons additionally accelerated during their movement in said second closed path are returned from said second closed path to said first closed path, the cycle of operations described then repeating, with the electrons gaining energy with each switching operation.

35 Finally, after a predetermined number of accelerations have been imparted to the electrons, the same are released, whereupon the tremendous energy gained thereby may be put to any appropriate use.

In the accompanying specification there shall be described, and in the annexed drawings shown, an illustrative embodiment of the magnetic induction device of the present invention. It is, however, to be clearly understood that the present

invention is not to be limited to the details herein shown and described for purposes of illustration only, inasmuch as changes therein may be made without the exercise of invention, and within the true spirit and scope of the claims hereto appended.

In said drawings,

Fig. 1 is a longitudinal sectional view taken substantially through the center of a magnetic induction device assembled in accordance with the present invention;

Fig. 2 is a transverse sectional view taken on line 2—2 of Fig. 1; and

Fig. 3 is a schematic diagram of one way in which the electrical components included in the present invention may be connected to a power source.

Referring now more in detail to the aforesaid illustrative embodiment of the present invention, with particular reference to Figs. 1 and 2 of the drawings, the numeral 10 generally designates an hermetically sealed envelope made, preferably, of glass, and comprising, preferably, a centrally-disposed, main body portion 11 of rectangular cross section, from which extends, in opposite directions, a pair of loop-like, auxiliary body portions 12 and 13 each of which is, preferably, of circular cross-section and communicates, at the opposite ends thereof, with said main body portion 11.

Mounted at one end of the main body portion 11 is an electron gun 14 comprising an electron-emissive cathode 15, a perforate accelerating electrode 16, and a perforate focusing electrode 17, whereby a thin stream of electrons can be introduced into the interior of said envelope 10.

Mounted within the main body portion 11 is a pair of conducting plates 18 and 19 between which, as will hereinafter be more fully described, an electric field is adapted to be established, and surrounding said main body portion 11 is a coil 20 by means of which, also as will hereinafter be more fully described, a magnetic field is adapted to be established lengthwise through said main body portion, parallel to and intermediate the plates 18 and 19.

The mutually perpendicular electric and magnetic fields thus established are in such directions, and are of such relative intensities, that the stream of electrons coming from the gun 14 is deflected, as indicated by the broken line marked A, so as to enter the lower curved portion 21 of the auxiliary body portion 12.

Disposed at spaced intervals about the lower portion 21 of the auxiliary body portion 12 is a plurality of substantially U-shaped electromagnets 22, alternate magnets having their pole pieces 23 and 24 straddling the envelope and converging inwardly, and intermediate magnets having their pole pieces 25 and 26 straddling the envelope and diverging outwardly, whereby there is established along the length of the lower portion 21 of the auxiliary body portion 12 a plurality of transverse magnetic fields the lines of force of which bow outwardly. The radial variation in these fields should be such as to result in stabilizing the orbits of the moving electrons.

The interaction of the magnetic fields thus established with the moving electrons entering the lower portion 21 of the auxiliary body portion 12 causes said electrons to be subjected to a force which holds them in a path following the contour of said lower portion 21. The electrons, in the device as thus far described, move at a substantially uniform speed substantially equal to

that with which they are emitted from the gun 14.

As the electrons leave the lower curved portion 21 of the auxiliary body portion 12, they enter a straight portion 27, and in order to accelerate said electrons, it is necessary to subject them to one or more electromotive forces along the length of their orbit. For this purpose, a plurality of circular electromagnets 28 is disposed along the length of the straight portion 27 of the auxiliary body portion 12, said electromagnets linking the electron orbit within the envelope and, preferably, being coaxial therewith.

Each such electromagnet may comprise a closed core 29, which may be laminated, provided with a winding 30 uniformly distributed thereabout in such a manner that after coming around to the starting point, it winds back upon itself until it again returns to said starting point, all of the turns of said winding being in the same direction. When such a winding is energized, a magnetic field is established within the core, but no field appears externally of said core, and when the energizing current is varied with time, said field gives rise to a time-varying electromotive force along the axis of said electromagnet, no part of said magnetic field, however, invading the region containing said electromotive force. As the moving electrons are impelled by the driving electromotive force thus created along the length of the straight portion 27 of the auxiliary body portion 12, they are accelerated.

As the accelerated electrons leave the straight portion 27 of the auxiliary body portion 12, they enter an upper curved portion 31 which, like the lower curved portion 21, is provided along the length thereof with a plurality of path-controlling electromagnets 22.

As the electrons leave the upper curved portion 31 of the auxiliary body portion 12, they return to the main body portion 11, and move in a straight line therethrough to complete a first closed path, whereupon they again enter the lower curved portion 21 to start another excursion around said first closed path. Said first closed path has been indicated in the drawings by the broken line marked B.

The electromagnets 28 may be energized, as will hereinafter be more fully described, by a 60-cycle alternating current, and during the first positive alternation of said current, the electrons make many excursions about the path B, each excursion resulting in acceleration to a greater velocity.

Means, to be hereinafter more fully described, are provided whereby at the end of the above referred to first positive alternation of the current energizing the electromagnets 28, an electric field is established between the plates 18 and 19 in such direction that, in cooperation with the magnetic field of the coil 20, it causes the electrons entering the main body portion 11 from the upper curved portion 31 of the auxiliary body portion 12 to be deflected so as to move along the path indicated in the drawings by the reference character C and enter the lower curved portion 32 of the auxiliary body portion 13 of the envelope 10.

Spaced along the length of the lower curved portion 32 of the auxiliary body portion 13 is a plurality of electromagnets 33, similar to the electromagnets 22, but so energized that the fields thereof are of opposite polarity for the reason that, where as in the auxiliary body portion 12, the electron movement was assumed to be in a clockwise direction, in the auxiliary body por-

tion 13, it will be seen that the electron movement is in a counter-clockwise direction. Also, as in the case of the electromagnets 22, the pole pieces 34 and 35 of alternate electromagnets 33 straddle the envelope and converge inwardly, while the pole pieces 36 and 37 of intervening electromagnets 33 straddle the envelope and diverge outwardly.

As the electrons leave the lower curved portion 32 of the auxiliary body portion 13, they enter a straight portion 38 which, like the straight portion 27 of the auxiliary body portion 12, is linked by a plurality of circular electromagnets 39. The latter include laminated cores 40 and windings 41, said windings 41 being energized in phase opposition to the energizing of the electromagnets 28 linking the straight portion 27. By this, it is meant that in the device as shown in Fig. 1, the electromotive forces induced by the electromagnets 28 and 39 are displaced in time phase by 180°. Thus, the electrons entering the straight portion 38 of the auxiliary body portion 13 are additionally accelerated.

As the additionally accelerated electrons leave said straight portion 38, they enter the upper curved portion 42 of the auxiliary body portion 13, wherein, by means of another group of electromagnets 33, they are guided back to the main body portion 11, through which, in the absence of any electric field between the plates 18 and 19, they pass to again enter the lower curved portion 32 of the auxiliary body portion 13, thereby completing an excursion through a second closed path, indicated by the reference character D.

During the first positive half-cycle of the current energizing the electromagnets 39, the electrons make many excursions over the path D, and with each excursion they become still further accelerated. As the end of said half-cycle, an electric field, of opposite polarity to the field which caused the electrons to move from path B to path D by way of path C, is established between the plates 18 and 19, whereby said electrons are caused to reenter the lower curved portion 12, by way of the path marked E, and commence additional excursions over the path B.

By thus switching the electrons between the paths B and D at the end of each half-cycle of the driving electromotive force, tremendous velocities and alterations in mass are obtained after a few cycles of said driving force. After a predetermined number of such cycles, the intensity of the electric field established between the plates 18 and 19 may be made such as to result in the electrons passing out of the main body portion 11 through the end 43 thereof, whereupon the energy gained by said electrons may be put to any appropriate use.

In order to prevent negative space charge from reducing the number of electrons travelling in the closed orbits hereinbefore referred to, it is desirable to provide the inner surfaces of the auxiliary body portions 12 and 13 of the envelope 10 with a plurality of spaced metallic coatings 10', each of said coatings being connected to the positive terminal of a source of voltage (not shown), the negative terminal of which may be connected to the cathode 15 of the electron gun 14. Preferably, the potential of said coatings with respect to the cathode of said gun should be about the same as the potential of the accelerating electrode 16 of said gun.

Reference is now made to Fig. 3 of the draw-

ings, wherein a schematic diagram for electrically connecting the components of the device of the present invention is set forth.

As there shown, a portion of the output of an alternating voltage generator 44, which may be of a frequency, for example, of 60 cycles per second, is applied to the accelerating electromagnets 28 to induce an electromotive force in the auxiliary body portion 12 of the envelope 10, the direction of said electromotive force being assumed to be such as to drive the electrons about the closed path B in a clockwise direction viewing Fig. 1.

Another portion of the output of the generator 44 is applied through a phase inverter 45, to the accelerating electromagnets 39, to induce an electromotive force in the auxiliary body portion 13 of the envelope 10, the direction of said last-named electromotive force being such as to drive the accelerated electrons switched from the auxiliary body portion 12 to the auxiliary body portion 13 about the closed path D in a counter-clockwise direction viewing Fig. 1, the phase inverter 45 displacing the electromotive forces developed by the electromagnets 28 and 39 in time phase by 180°.

A third portion of the output of the generator 44 is applied to a rectifier 46, the resulting direct current being applied to the coil 20 in such direction, for example, that the north magnetic pole of the coil 20 is located adjacent the end of the main body portion 11 opposite the electron gun 14.

A fourth portion of the output of the generator 44 is applied, through a phase shifter 47, to a frequency multiplier 48, for example, a frequency doubler, and the output of the latter is applied to a pulse generator 49 adapted to transform the sine-wave output of the generator 44 into flat-topped pulses of extremely short duration, for example, .1 microsecond, said generator 49 also including means for increasing the amplitude of successive pulses generated thereby over a predetermined number of cycles of the initial voltage produced by the generator 44.

The pulses thus obtained are applied to the plates 18 and 19 through a switch 50 designed to reverse the polarity of successive pulses.

The purpose of the frequency multiplier 48 is to enable the production of a pulse corresponding to each half-cycle of the driving electromotive force; the purpose of the phase shifter 47 is to enable the adjustment of the time of the application of the switching pulses to coincide with the end of each half-cycle of said driving electromotive force; the purpose of increasing the amplitude of successive pulses produced by the generator 49 is to take into account the increased velocity of the electrons at each successive switching operation; and the purpose of the polarity switch 50 is to enable reversal of the direction of the electric field set up between the plates 18 and 19 during successive switching operations so that, at one time, the electrons are deflected away from the path B to the path D, and, at the next time, from the path D back to the path B.

A fifth portion of the output of the generator 44 is applied to a frequency divider 51, one portion of the output of the latter being applied to the path-controlling electromagnets 22, and another portion of said output being applied, through a phase inverter 52, to the path-controlling electromagnets 33.

Assuming that the electrons are to be accel-

erated during five successive cycles of the voltage produced by the generator 44, it is necessary that each time, during said five cycles, that the electrons pass by the path-controlling electromagnets, the fields established by the latter be of increased intensity in order to compensate for the augmented velocity attained by said electrons with each excursion. This may be accomplished by applying to the path-controlling electromagnets energizing current of a sub-multiple frequency of the driving electromotive force. In the case under consideration, inasmuch as the gradually increasing field intensity must cover the time of five cycles of the driving electromotive force, the frequency of the energizing current applied to the path-controlling electromagnets should be three cycles per second.

This completes the description of the aforesaid illustrative embodiment of the present invention. It will be noted from all of the foregoing that by means of the magnetic induction device of the present invention, charged particles, such as electrons, may be repeatedly accelerated during many half cycles of the driving electromotive force, thereby enabling the attainment, with less driving force than has heretofore been used, of extremely high energies. It will further be noted that the magnetic induction device of the present invention is so constructed that it is necessary to incorporate therein, in order to arrive at a given energy, considerably less iron than has heretofore been the case, thereby materially reducing the cost, weight and size of the device.

Other objects and advantages of the present invention will readily occur to those skilled in the art to which the same relates.

What is claimed is:

1. A magnetic-induction device comprising: an evacuated envelope; a source of electrons, disposed in said envelope, for introducing electrons therein; a first magnetic structure, mounted adjacent said envelope, for establishing a first magnetic field transversely therethrough; said first magnetic field coacting with said electrons to subject them to a first force, causing the same to move in a first closed path; a second magnetic structure, linking said envelope, for inducing along said first closed path a first, time-varying electromotive force; said first, time-varying electromotive force coacting with the electrons moving in said first closed path to subject them to a second force, causing the same to become accelerated; means, mounted adjacent said first closed path, for establishing a third, force-producing field therethrough; said third, force-producing field coacting with said accelerated electrons to displace the same from said first closed path; a third magnetic structure, mounted adjacent said envelope, for establishing a second magnetic field transversely therethrough; said second magnetic field coacting with said displaced electrons to subject them to a fourth force, causing the same to move in a second closed path; and a fourth magnetic structure, linking said envelope, for inducing along said second closed path a second, time-varying electromotive force; said second, time-varying electromotive force coacting with the electrons moving in said second closed path to subject them to a fifth force, causing the same to become additionally accelerated.

2. A magnetic-induction device comprising: an evacuated envelope; a source of electrons, disposed in said envelope, for introducing electrons therein; a first magnetic structure, mounted ad-

jacent said envelope, for establishing a first magnetic field transversely therethrough; said first magnetic field coacting with said electrons to subject them to a first force, causing the same to move in a first closed path; a second magnetic structure, linking said envelope, for inducing along said first closed path a first, time-varying electromotive force; said first, time-varying electromotive force coacting with the electrons moving in said first closed path to subject them to a second force, causing the same to become accelerated; a third magnetic structure, mounted adjacent said envelope for establishing a second magnetic field transversely therethrough; said second magnetic field coacting with said accelerated electrons to subject them to a third force, causing the same to move in a second closed path; a fourth magnetic structure, linking said envelope, for inducing along said second closed path a second, time-varying electromotive force; said second, time-varying electromotive force coacting with the electrons moving in said second closed path to subject them to a fourth force, causing the same to become additionally accelerated; and a partially magnetic, partially electrostatic structure, mounted adjacent said closed paths, for recurrently establishing magnetic and electrostatic fields therethrough; said last-named magnetic and electrostatic fields coacting with said electrons to subject them to a fifth force, causing the same to switch successively between said closed paths.

3. A magnetic-induction device comprising: an evacuated envelope having a main body portion, and two auxiliary body portions extending from and communicating with said main body portion; a source of electrons, disposed in the main body portion of said envelope, for introducing electrons therein; a first magnetic structure, mounted adjacent one of the auxiliary body portions of said envelope, for establishing a first magnetic field transversely therethrough; said first magnetic field coacting with said electrons to subject them to a first force, causing the same to move in a first closed path including the main and said one of said auxiliary body portions of said envelope; a second magnetic structure, linking said one of said auxiliary body portions of said envelope, for inducing along said first closed path a first, time-varying electromotive force; said first, time-varying electromotive force coacting with the electrons moving in said first closed path to subject them to a second force, causing the same to become accelerated; means, mounted adjacent said first closed path, for establishing a third, force-producing field therethrough; said third, force-producing field coacting with said accelerated electrons to displace the same from said first closed path; a third magnetic structure, mounted adjacent the other of the auxiliary body portions of said envelope, for establishing a second magnetic field transversely therethrough; said second magnetic field coacting with said displaced electrons to subject them to a fourth force, causing the same to move in a second closed path including said main and said other of said auxiliary body portions of said envelope; and a fourth magnetic structure, linking said other of said auxiliary body portions of said envelope, for inducing along said second closed path a second, time-varying electromotive force; said second, time-varying electromotive force coacting with the electrons moving in said second closed path to subject them to a fifth force, causing the same to become additionally accelerated.

4. A magnetic-induction device comprising: an evacuated envelope having a main body portion, and two auxiliary body portions extending from and communicating with said main body portion; a source of electrons, disposed in the main body portion of said envelope, for introducing electrons therein; a first magnetic structure, mounted adjacent one of the auxiliary body portions of said envelope, for establishing a first magnetic field transversely therethrough; said first magnetic field coacting with said electrons to subject them to a first force, causing the same to move in a first closed path including the main and said one of said auxiliary body portions of said envelope; a second magnetic structure, linking said one of said auxiliary body portions of said envelope, for inducing along said first closed path a first, time-varying electromotive force; said first, time-varying electromotive force coacting with the electrons moving in said first closed path to subject them to a second force, causing the same to become accelerated; a third magnetic structure, mounted adjacent the other of the auxiliary body portions of said envelope, for establishing a second magnetic field transversely therethrough; said second magnetic field coacting with said accelerated electrons to subject them to a third force, causing the same to move in a second closed path including said main and said other of said auxiliary body portions of said envelope; and a fourth magnetic structure, linking said other of said auxiliary body portions of said envelope, for inducing along said second closed path a second, time-varying electromotive force; said second, time-varying electromotive force coacting with the electrons moving in said second closed path to subject them to a fourth force, causing the same to become additionally accelerated; and a partially magnetic, partially electrostatic structure, mounted adjacent said closed paths, for recurrently establishing magnetic and electrostatic fields therethrough; said last-named magnetic and electrostatic fields coacting with said electrons to subject them to a fifth force, causing the same to switch successively between said closed paths.

5. A magnetic-induction device comprising: an evacuated envelope; a source of electrons, disposed in said envelope, for introducing electrons therein; a first group of opposed, alternately converging and diverging, U-shaped magnets, each of which partially surrounds said envelope, for establishing a first magnetic field transversely therethrough; said first magnetic field coacting with said electrons to subject them to a first force, causing the same to move in a first closed path; a first group of toroidal electromagnets, each of which links said envelope, for inducing along said first closed path a first, time-varying electromotive force; said first, time-varying electromotive force coacting with the electrons moving in said first closed path to subject them to a second force, causing the same to become accelerated; means, mounted adjacent said first closed path, for establishing a third, force-producing field therethrough; said third, force-producing field coacting with said accelerated electrons to displace the same from said first closed path; a second group of opposed, alternately converging and diverging, U-shaped magnets, each of which partially surrounds said envelope, for establishing a second magnetic field transversely therethrough; said second magnetic field coacting with said displaced electrons to subject them to a fourth force, causing the same to move in

a second closed path; and a second group of toroidal electromagnets, each of which links said envelope, for inducing along said second closed path a second, time-varying electromotive force; said second, time-varying electromotive force coacting with the electrons moving in said second closed path to subject them to a fifth force, causing the same to become additionally accelerated.

6. A magnetic-induction device comprising: an evacuated envelope; a source of electrons, disposed in said envelope, for introducing electrons therein; a first group of opposed, alternately converging and diverging, U-shaped magnets, each of which partially surrounds said envelope, for establishing a first magnetic field transversely therethrough; said first magnetic field coacting with said electrons to subject them to a first force, causing the same to move in a first closed path; a first group of toroidal electromagnets, each of which links said envelope, for inducing along said first closed path a first, time-varying electromotive force; said first, time-varying electromotive force coacting with the electrons moving in said first closed path to subject them to a second force, causing the same to become accelerated; a second group of opposed, alternately converging and diverging, U-shaped magnets, each of which partially surrounds said envelope, for establishing a second magnetic field transversely therethrough; said second magnetic field coacting with said accelerated electrons to subject them to a third force, causing the same to move in a second closed path; a second group of toroidal electromagnets, each of which links said envelope, for inducing along said second closed path a second, time-varying electromotive force; said second, time-varying electromotive force coacting with the electrons moving in said second closed path to subject them to a fourth force, causing the same to become additionally accelerated; an electromagnet surrounding a portion of said envelope including portions of said closed paths; and a pair of spaced plates mounted in the portion of said envelope surrounded by said electromagnet; said electromagnet and said spaced plates being adapted recurrently to be energized to establish magnetic and electrostatic fields coacting with said electrons to subject them to a fifth force, causing the same to switch successively between said closed paths.

7. A magnetic-induction device comprising: an evacuated envelope having a main body portion, and two auxiliary body portions extending from and communicating with said main body portion; a source of electrons, disposed in the main body portion of said envelope, for introducing electrons therein; a first group of opposed, alternately converging and diverging, U-shaped magnets, each of which partially surrounds one of the auxiliary body portions of said envelope, for establishing a first magnetic field transversely therethrough; said first magnetic field coacting with said electrons to subject them to a first force, causing the same to move in a first closed path including the main and said one of said auxiliary body portions of said envelope; a first group of toroidal electromagnets, each of which links said one of said auxiliary body portions of said envelope, for inducing along said first closed path a first, time-varying electromotive force; said first, time-varying electromotive force coacting with the electrons moving in said first closed path to subject them to a second force, causing the same to become accelerated; means, mounted adjacent said first closed path, for establishing a third, force-producing field therethrough; said third, force-producing field coacting with said displaced electrons to subject them to a fourth force, causing the same to move in

11

mounted adjacent said first closed path, for establishing a third, force-producing field therethrough; said third, force-producing field coaxing with said accelerated electrons to displace the same from said first closed path; a second group of opposed, alternately converging and diverging, U-shaped magnets, each of which partially surrounds the other of the auxiliary body portions of said envelope, for establishing a second magnetic field transversely therethrough; said second magnetic field coaxing with said displaced electrons to subject them to a fourth force, causing the same to move in a second closed path including said main and said other of said auxiliary body portions of said envelope; and a second group of toroidal electromagnets, each of which links said other of said auxiliary body portions of said envelope, for inducing along said second closed path a second, time-varying electromotive force; said second, time-varying electromotive force coaxing with the electrons moving in said second closed path to subject them to a fifth force, causing the same to become additionally accelerated.

8. A magnetic-induction device comprising: an evacuated envelope having a main body portion, and two auxiliary body portions extending from and communicating with said main body portion; a source of electrons, disposed in the main body portion of said envelope, for introducing electrons therein; a first group of opposed, alternately converging and diverging, U-shaped magnets, each of which partially surrounds one of the auxiliary body portions of said envelope, for establishing a first magnetic field transversely therethrough; said first magnetic field coaxing with said electrons to subject them to a first force, causing the same to move in a first closed path including the main and said one of said auxiliary body portions of said envelope; a first group of toroidal electromagnets, each of which links said one of said auxiliary body portions of said envelope, for inducing along said first closed path a first, time-varying electromotive force; said first, time-varying electromotive force coaxing with the electrons moving in said first closed path to subject

12

them to a second force, causing the same to become accelerated; a second group of opposed, alternately converging and diverging, U-shaped magnets, each of which partially surrounds the other of the auxiliary body portions of said envelope, for establishing a second magnetic field transversely therethrough; said second magnetic field coaxing with said accelerated electrons to subject them to a third force, causing the same to move in a second closed path including said main and said other of said auxiliary body portions of said envelope; a second group of toroidal electromagnets, each of which links said other of said auxiliary body portions of said envelope, for inducing along said second closed path a second, time-varying electromotive force; said second, time-varying electromotive force coaxing with the electrons moving in said second closed path to subject them to a fourth force, causing the same to become additionally accelerated; an electromagnet surrounding said main body portion of said envelope; and a pair of spaced plates mounted in said main body portion; said electromagnet and said spaced plates being adapted recurrently to be energized to establish magnetic and electrostatic fields coaxing with said electrons to subject them to a fifth force, causing the same to switch successively between said closed paths.
